CLAIM

The ornamental design for a turn signal, as shown and described.

DESCRIPTION

FIG. 1 is a perspective view of the turn signal.

FIG. 2 is a front elevational view of the turn signal of FIG. 1.

FIG. 3 is a top plan view of the turn signal of FIG. 1.

FIG. 4 is a back elevational view of the turn signal of FIG. 1.

FIG. 5 is a bottom view of the turn signal of FIG. 1.

FIG. 6 is a left side elevational view of the turn signal of FIG. 1; and,

FIG. 7 is a right side elevational view of turn signal of FIG. 1.

The broken lines in the drawings form no part of the claimed design.
